UNITED STATES PATENT OFFICE.

LEE MURRAY, OF MINNEAPOLIS, MINNESOTA, ASSIGNOR TO DURKEE-ATWOOD COMPANY, OF MINNEAPOLIS, MINNESOTA, A CORPORATION OF MINNESOTA.

COLLAPSIBLE VULCANIZING FORM.

1,404,217.

Specification of Letters Patent. Patented Jan. 24, 1922.

Application filed February 28, 1921. Serial No. 448,569.

To all whom it may concern:

Be it known that I, LEE MURRAY, a citizen of the United States, resident of Minneapolis, county of Hennepin, State of Minnesota, have invented certain new and useful Improvements in Collapsible Vulcanizing Forms, of which the following is a specification.

In the operation of making belts of rubberized fabric, it is customary to place them in a vulcanizing oven as a final step in the belt-making process.

The object of my present invention is to provide an improved type of form or support for the belts during this vulcanizing process, the form being of such construction that it will support a number of the belts and when removed from the vulcanizing oven and is too hot to be handled, the form can be collapsed and the belts released with comparatively little effort on the part of the attendant and without any danger of being burned.

A further object is to provide a form of light, durable construction which can be easily and quickly filled or loaded with the belts and as readily separated therefrom when the vulcanizing process is completed.

The invention consists generally in various constructions and combinations, all as hereinafter described and particularly pointed out in the claims.

In the accompanying drawings forming part of this specification,

Figure 1 is a plan view of a vulcanizing form embodying my invention,

Figure 2 is a cross sectional view on line 2-2 of Figure 1,

Figure 3 is a similar view, showing the form in its collapsed position to release the belts,

Figure 4 is a perspective view of the clip used for holding the abutting edges of the form in alignment when the form is filled with the belts and during the vulcanizing operation.

In the drawing, 2 represents the wall of the form, consisting preferably of sheet metal bent to a cylindrical form of suitable diameter, according to the size of the belt. The peripheral surface of this form is provided with a series of annular grooves 3 arranged in spaced relation in the form. These grooves are adapted to receive a round belt, so called, made of rubberized fabric and

cylindrical in cross section. The belts after the stretching operation are placed in the grooves in the form and then placed with the form in a vulcanizing oven.

One longitudinal edge of the form has a plate 4 mounted thereon and projecting beyond the edge of the plate to form a seat for the other edge when the form is expanded to assume a cylindrical shape preparatory to vulcanizing. This form in effect consists of a section or pipe that is divided longitudinally, the abutting edges being held in alignment by the plate 4. At each end of the form I prefer to provide clips 5 which bridge the joint at the abutting ends and serve to hold the edges in alignment, preventing one edge from snapping or slipping by the other and allowing the form to collapse until the attendant is ready to remove the belts after the vulcanizing operation. These clips may be made in any suitable way, but preferably by bending or folding the piece of metal over upon itself to form wings between which the abutting edges of the cylinder are received and held. As soon as these clips are removed, the belts are unseated from the grooves by any suitable means and the form is collapsed sufficiently to allow the convenient removal of the belts.

I claim as my invention:

1. A vulcanizing form for belts comprising a member having an annular peripheral seat to receive an endless belt, said member being collapsible for removal of the belt after vulcanizing.

2. A vulcanizing form for belts, comprising a member having a plurality of annular peripheral seats, each adapted to receive an endless belt, said member being collapsible for removal of the belts after vulcanizing.

3. A vulcanizing form comprising a sheet metal cylindrical member divided longitudinally and having a plurality of annular grooves in its outer surface adapted to receive fabric belts, cylindrical in cross section, said member being adapted to collapse and relieve outward pressure on said belts, and means for holding the abutting edges of said member in alignment when the form is in use.

4. A vulcanizing form for belts comprising a member having a plurality of annular peripheral seats each adapted to receive an endless belt, cylindrical in cross section, said

member being collapsible for removal of the belts after vulcanizing.

5. A vulcanizing form comprising a sheet metal cylindrical member divided longitudinally and having a plurality of annular grooves in its outer surface adapted to receive fabric belts, said member being adapt-

ed to collapse and relieve outward pressure on said belts, and means for holding the abutting edges of said member in alignment when the form is in use.

In witness whereof, I have hereunto set my hand this 23d day of February 1921.

LEE MURRAY.
